ATTORNEY.

UNITED STATES PATENT OFFICE

BRUCE FORD, OF PHILADELPHIA, PENNSYLVANIA

BURNED OR PUDDLED JOINT STRUCTURE

Application filed February 3, 1926. Serial No. 85,621.

The present invention relates to improvements in burned or puddled joint structures for connecting abutting members or parts, such as the members or parts of storage batteries and their accessories, which usually consist of lead or lead alloy.

The principal object of the present invention is to obviate the use of a detachable dam structure for providing a pocket for molten metal and to avoid the care and labor necessary for applying, removing and supporting such a dam structure.

To these and other ends hereinafter set forth the invention comprises a burned or puddled joint structure for connecting abutting elements which includes interfitting walls provided on the abutting elements and providing between them an open pocket for molten metal.

20 The invention also comprises the improvements to be presently described and finally claimed.

In the following description reference will be made to the accompanying drawing forming part hereof and in which there is illustrated an embodiment of the invention chosen from among other embodiments of the invention for the sake of illustration and in which

Figure 1 is a top or plan view.

30 Fig. 2 is a central sectional elevational view of Figure 1, also showing the metal in the joint, and

Figs. 3 and 4 are perspective views showing the parts in separate relation.

35 In the drawing 1 and 2 indicate elements which are to be connected in abutting relation by puddling or burning. Obviously the form of the elements 1 and 2 is subject to great diversity. There are interfitting walls provided on the abutting elements and they afford or provide between them an open pocket 3 for retaining molten metal by which the joint is burned or puddled. The molten metal is shown in Fig. 2 at 3^a. Of the interengaging walls 4 and 5 are tongues and grooves, and 6 and 7 are laps.

To make the burned or puddled joint the walls are placed in interfitting relation, thus providing a pocket 3 which serves to retain molten metal.

The term puddling or burning, as used commonly in the lead working and allied arts, means joining two pieces of metal together by flowing molten metal, preferably of the same composition as that of the pieces to be joined, over the abutting faces and melting the edges of the metallic surfaces to form an integral joint.

It will be obvious to those skilled in the art to which the invention relates that modifications may be made in details of construction and arrangement without departing from the spirit of the invention which is not limited as to those matters or as to matters of mere form or otherwise than as the prior art and the appended claims may require.

I claim:

1. A burned or puddled joint structure for connecting abutting elements which comprises overlapping and interengaging vertical side and horizontal walls provided on the abutting elements and affording between them a pocket open at the top and closed at the bottom, and metal burned or puddled into the pocket.

2. A burned or puddled joint structure for connecting abutting elements which comprises interfitting walls of which two are upright tongues and upright grooves and of which two are horizontal laps, and said walls providing between them a pocket open at the top and closed at the bottom, and metal burned or puddled into the pocket.

BRUCE FORD.
